DOUBLE LIFT SINGLE SCREW JACK

John A. Morrison, Warren, Ohio

Application July 28, 1933, Serial No. 682,561

6 Claims. (Cl. 254—102)

The invention relates to lifting jacks especially adapted for raising automobiles, trucks and other vehicles and more particularly to a double lift jack operated by a single screw. 5 Jacks of this particular type comprise two hollow or tubular lifting members adapted to be operated by a single screw, one lifting member being raised, by means of the screw, to a predetermined height at which point it is automatically locked to the other lifting member and disengaged from the screw while the second lifting member is automatically brought into engagement with the screw and raised thereby, carrying with it the first lifting member locked thereto in extended position.

The object of the present improvement is to provide a simple, inexpensive and efficient lifting jack having two lifting members successively operated by a single screw.

20 A further object is to provide a lifting jack of this character which does not require the use of any extra locking means, one of the lifting members being automatically locked directly to the other lifting member at a predetermined position during the operation of the jack.

Another object is to provide a jack of this character comprising two telescoping tubular lifting members with means for preventing turning of one member and means for causing the other member to turn at a predetermined time to lock the two members together when the inner member has reached the limit of its movement relative to the outer member.

A still further object of the improvement is to 35 provide such a lifting jack in which the outer tubular lifting member is provided with one or more openings near its upper end and the inner lifting member is provided with one or more lugs or projections near its lower end adapted to be automatically engaged in said openings when the inner member has reached a predetermined height, whereby the inner and outer members are directly locked to each other.

The above objects, together with others which 45 will be readily apparent from the following description and the accompanying drawing, or which may be later pointed out, may be attained by constructing the improved lifting jack in the manner illustrated in the drawing, in which

Figure 1 is a vertical sectional view of the improved jack showing the same in the lowered or collapsed position, taken as on the line 1—1, 55 Fig. 2;

Fig. 2, a top plan view with the lifting cap removed;

Fig. 3, a vertical sectional view of the upper portion of the housing of the jack;

Fig. 4, a sectional elevation of the upper portion of the housing showing the outer tubular lifting member and the lower portion of the inner lifting member in the raised or extended position;

Fig. 5, a transverse section through the housing taken as on the line 5—5, Fig. 3;

Fig. 6, a transverse sectional view through the locking portions of the inner and outer lifting members in locked position, taken as on the line 6—6, Fig. 4;

Fig. 7, a detail perspective view of the lower portion of the inner lifting member; and

Fig. 8, a similar view of the upper portion of the outer lifting member.

Similar numerals refer to similar parts throughout the drawing.

A tubular housing 10 is provided for normally enclosing the moving parts of the jack when in closed position, this housing being preferably in the form of a casting enlarged at its lower end as 80 shown at 11 and 12 and connected to the base 13 as by rivets 14 or the like forming a housing for the bevel gear 15 and the bevel driving pinion 16 which meshes therewith.

The pinion 16 is fixed upon the inner end of a 85 short shaft 17 journaled in the bearing 18 preferably formed integral with the enlarged portion 11 of the housing and having a socket 19 for receiving the ordinary operating handle such as is commonly used for raising and lowering jacks of 90 this general character.

The gear 15 is axially fixed upon the vertical lifting screw 20, the lower end of which is journaled in the thrust bearing 21 formed in the base 13.

The outer lifting member 22 is tubular in form, preferably square in cross section as shown, and is mounted for vertical movement within the housing 10, being provided at its lower end with the nut 23 normally receiving the unthreaded 100 portion 24 of the screw 20, when the jack is in the lowered or collapsed position, as shown in Fig. 1.

The inner lifting member 25 is also of tubular form, preferably square in cross section, and is 105 slideable within the outer member 22, being provided at its lower end with the nut portion 26 normally engaged by the screw 20 when the jack is in lowered position as shown in Fig. 1.

A stud 27 is fixed in the lower end portion of 110

the inner lifting member 25 and extends through the vertical slot 28 formed in one side of the outer lifting member 22, the upper end of said slot having the angular horizontally disposed portion 29. 5 The stud 27 is also slidably received in the vertical groove 30 formed in the housing 10 in order to prevent axial movement of both of the lifting members during the time the inner lifting member is being raised to the limit of its movement relative to the outer lifting member.

10 The lower portion of the inner lifting member 25, just above the stud 27, is of reduced cross section, being preferably rounded as shown at 31 in Fig. 7, forming the lugs 32 below said reduced portion 15 and similar lugs 33 above the same.

15 The upper portion of the outer lifting member 22 is provided with openings 34 adapted to receive the lugs 32 when the two lifting members are locked together in extended position, as will be 20 later described, at which time the upper lugs 33 will rest upon the flat upper end 35 of the outer lifting member.

25 The outer lifting member 22 is provided near its upper end with a pair of studs 36 which are slidably received in the grooves 37 formed in the housing, said grooves having the inclined angular portions 37a near their upper ends terminating in the vertical upper ends 37b. The studs 36 cooperating with these grooves axially turn the 30 outer lifting member 22 from the position shown in Fig. 2 to that shown in Fig. 6, while the inner lifting member 25 is held against turning movement by the stud 27 riding in the vertical groove 30 of the housing, the angular offset portion 29 of the groove 28 in the outer lifting member accommodating the lug 27 as the outer lifting member is turned to the locked position.

35 In the operation of the jack, assuming that the parts are in the normal, or lowered position, as best shown in Fig. 1, the usual operating handle 40 is connected to the socket 19 in customary manner and rotated in the proper direction, whereby through the pinion 16 and gear 15 the screw 20 is rotated in a direction to raise the inner lifting member 25. The outer lifting member 22 at first remains stationary as the nut 23 thereof is not engaged by the screw.

45 As the inner lifting member is raised to a point where the stud 27 thereon reaches the upper end 50 of the slot 28 in the outer lifting member, the outer lifting member is pulled upward thereby until the nut 23 thereon is brought into engagement with the screw 20.

55 As the outer lifting member moves upward, the studs 36 thereon passing through the angular portions 37a of the grooves in the housing rotate the outer lifting member from the position shown in Fig. 2 to that shown in Fig. 6, the inner lifting member 25 being held against axial movement by the stud 27 engaged in the vertical groove 30 of the housing.

60 As the outer lifting member is rotated, the lugs 32 upon the inner lifting member will be engaged in the openings 34 of the outer lifting member, the stud 27 being received in the angular offset portion 29 of the slot 28, and the lugs 33 of the inner lifting member will engage over the flat upper end 35 of the outer lifting member.

65 As the rotation of the screw 10 continues, the nut 26 of the inner lifting member will pass upward out of engagement with the screw and the outer lifting member will continue to raise, carrying with it the fully extending inner lifting member locked thereto as above described.

70 The squared opening 38 in the upper end of

the housing holds the outer lifting member against turning relative to the screw as it proceeds to raise to the upper limit of its movement. The flanges 39 upon the lower end of the outer lifting member engaging the flange 40 at the upper end of the housing prevent the outer lifting member from being raised beyond this point so that the same cannot be accidentally disconnected from the screw.

75 A cap 41 of any suitable description may be carried by the upper end of the inner lifting member for engagement with the automobile axle or other portion of the vehicle, as in usual practice.

80 In order to lower the jack, the screw is rotated in the opposite direction, moving the outer lifting member downward until the studs 36 riding back through the inclined portions 37a of the grooves in the housing rotate the same sufficiently to unlock the inner lifting member therefrom, after which the nut upon the outer lifting member will pass out of engagement with the lower end portion of the screw, while the nut upon the inner lifting member will travel down the screw until the parts assume the normal 90 position as shown in Fig. 1.

I claim:

1. A lifting jack including a housing, a screw within the housing, means for rotating the screw, a pair of tubular lifting members normally telescoped within the housing, nuts upon the lower portions of said lifting members for engagement with the screw, means upon the lower end of one of the lifting members for locking engagement with the upper portion of the other lifting member and means for axially turning one of said lifting members at a predetermined position relative to the other lifting member and the housing to lock said lifting members together. 105

2. A lifting jack including a housing, a screw within the housing, means for rotating the screw, a pair of tubular lifting members normally telescoped within the housing, nuts upon the lower portions of said lifting members for engagement with the screw, the upper portion of one of the lifting members having openings therein, lugs upon the lower portion of the other lifting member for locking engagement with said openings, and means for axially turning one of said lifting members at a predetermined position relative to the other lifting member and the housing to lock said lifting members together. 110

3. A lifting jack including a housing, a screw within the housing, means for rotating the screw, a pair of tubular lifting members normally telescoped within the housing, nuts upon the lower portions of said lifting members for engagement with the screw, means upon the lower end of one of the lifting members for locking engagement with the upper portion of the other lifting member, and means upon the housing and one of the lifting members for axially turning said last named lifting member to lock the lifting members together. 120

4. A lifting jack including a housing, a screw within the housing, means for rotating the screw, a pair of tubular lifting members normally telescoped within the housing, nuts upon the lower portions of said lifting members for engagement with the screw, the upper portion of one of the lifting members having openings therein, lugs upon the lower portion of the other lifting member for locking engagement with said openings, and means upon the housing and one of the 130

lifting members for axially turning said last named lifting member to lock the lifting members together.

5. A lifting jack including a housing, a screw within the housing, means for rotating the screw, a pair of tubular lifting members normally telescoped within the housing, nuts upon said lifting members for engagement with the screw, lugs upon the lower end of the inner lifting member and apertures in the upper portion of the outer lifting member for locking engagement with said lugs, and coacting studs and inclined grooves in the outer lifting member and housing for automatically rotating the outer lifting member for locking the same to the inner lifting member when said inner lifting member has been raised to a predetermined point.

6. A lifting jack including a housing having inclined grooves therein, a screw within the housing, means for rotating the screw, a pair of tubular lifting members normally telescoped within the housing, nuts upon said lifting members for engagement with the screw, lugs at the lower end of the inner lifting member and openings at the upper end of the outer lifting member to receive said lugs, and studs upon said outer lifting member for engagement with the inclined grooves in the housing for automatically rotating the outer lifting member for locking the same to the inner lifting member when said inner lifting member has been raised to a predetermined point. 80
